FACE MASK

Paul B. Marasco, 1359 Chipeta Ave.,
Grand Junction, Colo.

Filed Aug. 26, 1958, Ser. No. 757,342

2 Claims. (Cl. 128—195)

This invention relates to a face mask for the medical treatment of patients with nebulized material.

Many patients are hospitalized throughout the world daily for the treatment of acute asthma, chronic pulmonary diseases such as emphysema, atelectasis, etc. and are treated, as a general rule with an aerosol mist or agent such as, for example, "Alevaire." As a general rule, the "Alevaire" mist treatment is accomplished by the use of compressed air as the source for operating the nebulizers supplying the mist. In other instances the patients' heads are placed in small tents, but in a far greater number of cases, most patients are instructed to hold the vapor discharge tube from the nebulizer proximate their noses or by placing the tubes in their mouths so that they may inhale the mist or vapor at intervals throughout the day and night. In other instances, and in order to facilitate the treatment inexpensively, patients will roll a newspaper into the shape of a funnel and connect the apex end thereof with the source of nebulized material and direct the base end towards their mouth and nose.

All of the equipment and methods referred to above are both inefficient and tiresome for the patient. Tents could be efficient but they have a number of undesirable features inherent in their use. For example, tents are bulky to store, and most adults do not like to lie in a tent covering only their heads for it is both confining and hot. It has been proposed to use a closed mask, but this type is expensive and the majority of the patients will not tolerate them.

Consequently, one of the primary objects of this invention is to provide means for oral and nasal medical treatment which obviates the inherent undesirable features of the apparatus referred to above.

A further object of this invention is to provide a face mask for connection with a nebulizer which is, for the most part, spaced from the mouth and nose of a patient.

Another object of this invention is to provide a face mask of the type generally referred to supra which is disposable.

A still further object of this invention is to provide a face mask with adjustable means for connecting the mask with the head of a patient.

The instant invention contemplates as a still further object thereof the provision of a face mask which may be manufactured from pliable plastics or disposable paraffined paper.

Yet another object of this invention is to provide a face mask which is non-complex in construction and assembly, inexpensive to manufacture, and durable in use.

Other and further objects and advantages of the instant invention will become more evident from a consideration of the following specification when read in conjunction with the annexed drawing, in which:

Figure 1 is a perspective view of a face mask constructed in accordance with this invention, this figure illustrating the application of the mask to the face of a

2

patient and with the mask being shown as connected to a nebulizer device;

Figure 2 is a vertical medial cross-sectional view of the face mask illustrated in a Figure 1; and,

Figure 3 is a back elevational view of the face mask, per se.

Referring now to the several figures of the drawings, reference numeral 10 designates, in general, a face mask constructed in accordance with the teachings of this invention. As is illustrated therein, the mask 10 comprises a substantially concave-convex front shield 12 truncated at its upper end 14 and having side portions 16, 18 adapted for engagement against the cheeks of a patient

20. The lower end 21 of the front shield terminates in a reverted concave-convex chin receiving cup 22. As is seen in the drawing, the convex side of the cup 22 confronts the concave side of the shield 12 but is not co-extensive therewith.

To the front shield 12 adjacent the lower end 21 thereof and substantially equidistant between the side portions 16, 18 projects an integrally formed hollow tubular connector element 24 adapted for connection with one end of a tubular conduit 26, the other end of the latter being connected with a vapor spout 28 of a nebulizer device 30.

Temple pieces 32 have one of their respective adjacent ends connected to the oppositely disposed upper corners of the shield 12 by any conventional type of connector 34. As is seen in Figures 1 and 2, these ends are provided with a plurality of longitudinally spaced openings 36 to permit adjustment of the mask 10 to accommodate the faces of patients having differing physical characteristics. The other ends of the temple pieces 32 terminate in ear engaging loops 38.

To utilize the mask 10, the conduit 26 which is formed of flexible material, is connected to the spout 28 and thereafter, the mask 10 is subtended from the ears of the patient, with the patient's chin engaging within the cup 22.

The cup 22 together with the temple pieces 32 cooperate to hold the mask 10 in closer or further spaced relation relative to the user's face, and the cup 22 serves the further purpose of condensing the larger ones of the atomized particles whereby the patient only breathes or inhales the finer ones thereof. The condensed particles are returned by gravity to the container of the nebulizer device 30.

The conduit 26 is detachably connected with the connector element 24 and the temple pieces 32 may be quickly released from the mask or shield 12 so that the mask 10 may be sterilized after use. That is, of course, assuming that the mask 10 is formed of a relatively rigid material such as plastic. However, if the mask is formed of paper or of other inexpensive material, the mask 10, after having been used by the patient is disconnected, as before, from the conduit 26 and the temple pieces are removed therefrom and saved for future use with a new mask. The mask 10, if formed of paper, may be then disposed in any desirable manner.

The temple pieces 32 in this instance are saved for subsequent use.

Having described and illustrated one embodiment of this invention, it will be understood that the same is offered merely by way of example, and that this invention is to be limited only by the scope of the appended claims.

What is claimed is:

1. A face mask for administering inhalable vaporous medicaments in the treatment of pulmonary disorders, comprising: a shield of a size and curved shape to fit around front and side portions of the face and under the chin of a patient, said shield having means thereon for holding it in position over the face of a patient with a bottom portion of the shield extending under the chin

of the patient, and with a space in the front portion of the shield opposite the mouth and nose of the patient in upward communication with the atmosphere and in direct communication with the bottom portion of the shield; inlet means in the bottom portion of the shield providing for admittance into the mask of medicament in vaporous form, and for directing such medicament toward the chin of a patient wearing the mask; and means on the shield inside the bottom portion thereof at a location spaced from but opposite said inlet, providing a deflector adapted to be impinged by vaporous medicament entering the mask through said inlet, said deflector cooperating with the front portions of the shield to define an uninterrupted upwardly extending passage in the front of the mask for conducting vaporous medicament directly and uninterruptedly from the inlet of the mask, past the patient's chin in bypass relation thereto, and into the space ahead of the patient's mouth and nose where the medicament, along with air entering the mask at the top thereof, may be readily inhaled by a patient wearing the mask, said deflector being shaped to provide a chin receiving cup having its forward edge portions spaced from the front of the shield and its side and rear edge portions connected to the bottom portion of the shield by a continuous joint so as to constrain all of the vaporous medicament entering the mask to flow upwardly through the space between the front of the cup and the front portion of the shield.

2. A face mask for administering inhalable vaporous medicaments in the treatment of pulmonary disorders, comprising: a shield of a size and curved shape to cover the front and side portions of the face and extend under the chin of a patient, said shield being formed to provide a space in the front portion thereof opposite the mouth and beneath the nose of the patient which space is in

upward communication with the atmosphere and in direct communication with the bottom portion of the shield; inlet means in the bottom portion of the shield providing for admittance into the mask of medicament in vaporous form, and for directing such medicament upwardly into the mask; and means on the shield inside the bottom rear portion thereof at a location adjacent to said inlet, providing a barrier adapted to extend under and in front of the chin of a patient wearing the mask to prevent medicament entering the mask through said inlet means from directly contacting the patient's chin, said barrier having a front portion spaced rearwardly from but cooperating with upright front portions of the shield to define an uninterrupted upwardly extending passage in the lower front portion of the mask for conducting vaporous medicament directly and uninterruptedly from the inlet means of the mask, past the patient's chin in bypass relation thereto, and into the space below the patient's nose and ahead of his mouth where the medicament, along with air entering the mask at the top thereof, may be readily inhaled by a patient wearing the mask, said barrier having its side and rear edge portions connected to the bottom rear portions of the shield by a continuous joint so as to constrain all of the vaporous medicaments entering the mask through said inlet means to flow upwardly through said passage and into said space.
